UNITED STATES PATENT OFFICE.

VINCENT UJKA, OF ST. LOUIS, MISSOURI, ASSIGNOR TO ORCHARD PAPER COMPANY, OF ST. LOUIS, MISSOURI, A CORPORATION OF MISSOURI.

DESIGN FOR TEXTILE FABRIC OR SIMILAR ARTICLE.

Application filed June 16, 1923. Serial No. 6,523. Term of patent 7 years.

To all whom it may concern:

Be it known that I, VINCENT UJKA, a citizen of the United States, and a resident of the city of St. Louis and State of Missouri, have invented a new, original, and ornamental Design for Textile Fabric or Similar Article, of which the following is a specification.

The accompanying drawing, which forms part of this specification is a face view of a piece of textile fabric showing the design.

I claim:

The ornamental design for textile fabric or similar article, as shown.

VINCENT UJKA.
